LIGHTING FIXTURE

Edwin F. Guth, Webster Groves, Mo.

Application October 29, 1932, Serial No. 640,210

5 Claims. (Cl. 240—78)

My invention relates to that class of lighting fixtures which are known as "indirect."

It is well known that the use of the so-called "total indirect" type of illumination causes or 5 produces a hollow effect upon the room due to the entire absence of local illumination.

To overcome this objection illuminating engineers have resorted to that type of fixture termed semi-indirect. These fixtures are 10 desirable from an artistic standpoint but lose many of the desirable advantages of the total indirect.

My invention has for its object to provide a fixture which will perform all of the functions 15 of a total indirect fixture but which will redirect some of the reflected rays into a bowl formed of diffusing glass serving to softly illuminate it, thereby overcoming the objectionable appearance of a total indirect fixture. A 20 further object of my invention is to obtain such illumination of the bowl without material loss of efficiency.

A further object of my invention is to provide a configuration for the glass bowl so that 25 the exterior of the opaque reflector employed for the indirect lighting will be slightly illuminated thereby removing the dark or black appearance of the indirect fixture.

My means of accomplishing the foregoing 30 objects may be more readily understood by having reference to the accompanying drawing which is hereunto annexed and made a part of this specification in which Fig. 1 is a side elevation of my improved lighting fixture, part 35 of the exterior being broken away to show the interior construction, the ceiling connection being shown broken off at one side;

Fig. 2 is a modified form; and

Fig. 3 is an enlarged detail view.

Similar reference numerals refer to similar 40 parts throughout the entire description.

As shown in the drawing the fixture is supported by a stem 1, the upper end of which is preferably provided with a swivel to ensure 45 its fixture hanging plumb, a canopy 3 is mounted at the ceiling to cover the outlet or junction box (not shown).

A socket 4 is secured to the lower end of the 50 stem 1, as illustrated, this is constructed in accordance with my Patent No. 1,722,743, but obviously any type of socket may be used.

A socket cover 5 encloses the upper part of the socket 4.

An opaque reflector 6 is suspended by wire 55 links 7.

The interior of the reflector 6 is preferably finished in white porcelain enamel. The upper ends of the links 7 are fastened to a collar 8 which is provided with threads 9 which fit the threads 10 on the socket 4. Though I have 60 described a specific suspension means it will be apparent to persons skilled in the art that any suitable or convenient means may be employed for this purpose.

An electric lamp bulb 11 is mounted in the 65 socket 4.

The reflector 6 is shown as an inverted bowl having a closed bottom but no particular configuration is requisite, for it will vary as the use to which it is to be put varies.

Adjacent the bottom of the reflector I form an annular groove channel or trough 12 the outer wall 13 of which is vertical and the inner wall 16 is inclined as shown. A multiplicity of 70 apertures 15 are punched in the inner wall 16 75 of the groove 12.

I secure a translucent glass bowl 24 to the bottom of the reflector 6 as shown, the lip 17 of the bowl 24 contacts the bottom of the reflector 6 just inside of the annular groove 12. This 80 bowl 24 may be secured to the reflector 6 in any desired manner; as shown in the drawing a screw 18 depends from the center of the reflector 6 and passes through an opening 19 formed in the glass bowl 24. A nut 20 serves to hold the 85 bowl securely in place. As clearly seen from the drawing I construct the bowl 24 so that it has a portion 21 which projects beyond the wall 13.

This feature may be dispensed with if desired. 90

The operation of my device is as follows: When the current is turned on and the lamp is illuminated some of the light rays will impinge upon the reflecting surface of the wall 13; these rays will be reflected and re-directed passing 95 through the apertures 15 into the globe 24, which will be thereby softly illuminated. When the bowl 24 is constructed so that it has the outwardly projecting portion 21, the light from this portion will light up the exterior surface of 100 the opaque reflector 6 sufficiently to eliminate any darkness thereof.

Although I have described in some detail the construction of a lighting fixture embodying my invention, it is not to be understood that 105 this is a limitation but merely to describe a preferred form and I do not wish to be limited thereto, except as such limitations appear in the claims.

Under some conditions it may be deemed de- 110

- sirable to have a completely enclosed unit. I accomplish this in the manner shown in Fig. 2 in which I provide a transparent glass cover 22 which has a central opening 23 which fits 5 the collar. When this cover 22 is in place it completely closes and covers the interior of the fixture. By forming it of transparent glass I am able to secure the desired result without loss of efficiency.
- Having described my invention, what I regard as new and desire to secure by Letters Patent is:
1. In a lighting fixture having a lamp, a support therefor, an opaque reflector having bottom and side walls, supporting means therefor, said reflector having an annular groove formed in the bottom adjacent the side wall, the outer wall of said groove being substantially vertical, the inner wall being inclined, a translucent globe 15 secured to the bottom of said reflector, there being a multiplicity of apertures through said inclined wall which are shielded from the direct rays of light whereby only reflected rays of light can reach said apertures and pass through 20 the interior of said translucent globe to illumine it.
  2. In a lighting fixture having a lamp, a support therefor, an opaque reflector having bottom and side walls, supporting means therefor, said reflector having an annular groove formed in the bottom adjacent the side wall, the outer wall of said groove being substantially vertical, the inner wall being inclined, a translucent globe 25 secured to the bottom of said reflector, there being a multiplicity of apertures through said inclined wall which are shielded from the direct rays of light whereby only reflected rays of light can reach said apertures and pass through the interior of said translucent globe
- to illumine it, said globe having an outwardly extending portion which softly illuminates the exterior of said opaque reflector.
3. In a lighting fixture having a light source, a support therefor, an inverted opaque reflector having a closed bottom wall, supporting means for said reflector, a plurality of apertures in the lower portion of said reflector substantially at the periphery of the bottom wall, a translucent bowl supported below the bottom of said reflector, said bowl having a peripheral portion extending inwardly thereof and covering said apertures whereby light rays, upon reflection, will pass said apertures and the inwardly extending portion of said bowl, thereby diffusely illuminating said bowl. 80 85 90
  4. A lighting fixture comprising an inverted opaque reflector provided with a closed bottom wall, a plurality of apertures in the bottom wall adjacent the periphery thereof, a translucent bowl mounted below the bottom wall and having a peripheral portion extending inwardly thereof below the peripheral portion of the bottom wall and covering said apertures. 95
  5. In a lighting fixture having a light source, a support therefor, an opaque reflector having a closed bottom wall and an upwardly facing substantially conical side wall, a channel formed between the bottom wall and the conical wall, a plurality of apertures in the inner wall of 100 105 said channel, a translucent bowl supported below the bottom of said reflector, said bowl having a peripheral portion extending inwardly thereof and covering said apertures, whereby light rays upon reflection will pass said apertures and the inwardly extended portion of said bowl, thereby diffusely illuminating said bowl. 110
